ABSTRACT OF THE DISCLOSURE

A machine for completing kneeling benches, or like articles, wherein components of the article, including a rigid base member, a cushion and a flexible cover member, are freely assembled in inverse order on a tray which is automatically driven along a conveyor path to means to fold the edges of the cover member over the longitudinal side edges of the base member, means to smooth and tension the folded-over side edges, and then to staplers that drive staples through the folded-over cover edges into the base member to complete the assembly. The tray is guided to prevent transverse movement, and the assembled components are compressed vertically with the base member held in the predetermined horizontal plane through the machine. All parts are freely adjustable for different widths and heights of articles.

BACKGROUND OF THE INVENTION

This invention relates to machines for automatically securing a flexible cover material to a solid base member while enclosing a cushioning material on the base member to produce a complete cushioning member.

In making articles such as box springs, chair backs, cushions, kneeling benches and similar articles, a bottom of solid wood, or a wood frame, is used to support a cushioning material, either foam or springs, and a flexible cover material is drawn tightly over the cushioning material and has its edges folded under, and secured to, the lower edge portions of the bottom. Usually, the covering is secured in place by having its inturned edges stapled along the lower sides of the bottom member.

The manufacture of articles of this nature has normally been a manual operation, requiring the services of skilled men in order to produce an acceptable product. Even when produced by skilled tradesmen, the operation is slow. The assembly of the materials, the precise and continuous compression of the cushioning material to just the right degree, plus the hand tacking, or stapling, is tedious and time-consuming. Naturally, high costs and limited production result.

SUMMARY OF THE INVENTION

The general object of the present invention is to provide an automatic machine which will be capable of feeding an assembly of base members, cushioning material and cover to mechanisms to properly compress the cushioning material, draw the cover material snugly and uniformly about the cushioning material, fold the side edges of the cover over the base member and staple the cover to the base while the parts are held in proper relation.

Another object of the invention is to provide a machine for this nature which is capable of continuous operation to draw the cover material in place and staple it irrespective of the length of assembled material fed to it.

A further object of the invention is the provision of means in a machine of this type which will enable the machine to be stopped during an assembly operation and to be restarted without harm to the article being produced.

Yet another object is to provide means to allow the

2

mechanism to be adjusted to receive assemblies of different width or depth, or both.

Still a further object of the invention is to provide a machine to produce the mentioned articles wherein the means for moving the assembled materials through the machine also serve as means to compress the cushioning material to the desired degree.

It is also an object to provide a machine wherein the materials of the article to be completed can be assembled in a tray in preliminary inverted position, and then moved into, and through, a machine on the tray.

Other objects of the invention will become apparent from the following description of one practical embodiment thereof, when taken in conjunction with the drawings which accompany, and form part of, this specification.

BRIEF DESCRIPTION OF THE DRAWINGS

FIG. 1 is a side elevation of a machine embodying the principles of the present invention;

FIG. 2 is a top plan view of the machine shown in FIG. 1;

FIG. 3 is a longitudinal, vertical section through the machine, taken substantially on the line 3—3 of FIG. 2;

FIG. 4 is a vertical, transverse section, taken on the line 4—4 of FIG. 3;

FIG. 5 is an exploded perspective view of one of the stapling units of the machine, together with its mounting means and part of its operating mechanism;

FIG. 6 is an exploded perspective view illustrating the tray for supporting the assembled materials and the materials in the order in which they will be placed in the tray;

FIG. 7 is a perspective view of part of an article after stapling; and

FIG. 8 is a view similar to FIG. 7, but with the end of the article being closed.

DETAILED DESCRIPTION OF THE PREFERRED EMBODIMENT

Although, the machine of the present invention can be used to complete articles such as box springs, chair backs and cushions, it will be disclosed in connection with the making of kneeling benches, as these are perhaps the simplest of the articles to be made and yet require the full operation of the machine.

The machine can be mounted upon any suitable frame. Frame 1, as shown, consists of vertical corner posts 2, arranged in a rectangular pattern, joined at their bottoms to a rectangular base frame 3. Base frame 3 extends transversely a considerable distance beyond the corner posts, and angularly extending braces 4 connect the outrigger portions of the base to the corner posts. At a distance above the base, at what will be substantially the working level of the machine, upper side frames 5 project outwardly from the corner posts to overlie portions of the outrigger parts of the base frame. These upper side frames are discontinuous transversely intermediate the adjacent corner posts. Transversely extending angle members 6, which join adjacent corner posts at the ends of the machine are located near the tops of the posts to hold the posts in proper spaced relation. Although other extensions of the basic frame will be described, the above-mentioned members constitute the frame.

Angle members 7 are attached to the inner sides of the corner posts 2 and extend longitudinally of the machine, projecting considerable distances beyond both ends of the frame. The length of the projection of the angle members 7 on the entrance end of the machine 8 is determined by the length of the articles to be produced, and can be any desired length. The same is true for the projection of the angle members 7 on the exit side 9 of the machine. Here, again, it will be necessary to support the completed articles as they emerge from the machine. The

lower, inwardly directed flanges of the angle members 7 form supports for channel side rails 10 of an article-supporting path completed by transversely extending rollers 11, which are located at spaced intervals along the full length of the side rails and have shafts 12 rotatably supported in the side rails. The rollers have their tops lying in the common horizontal plane to provide a rolling support for articles moved into, and from, the operating portion of the machine.

Turning now particularly to FIG. 6, it can be seen that the materials to produce the desired article are assembled in a tray 13, on which the materials are transported along the support path formed by the rollers 11 to and through, the operating mechanisms of the machine. The tray is composed of a flat bottom member 14 having angle members 15 extending along its sides. The vertical webs of the angle members are flush with the sides of the bottom and form vertical extensions of those sides. In order to give some preliminary shape to the materials as they are assembled, filler strips 16 are placed in the corners of the angle members 15. The tray will have a length equal to the article produced. In some instances, the assembled materials may be quite long and, when completed, cut into shorter lengths to be finished by closing the ends. In any event, the trays 13 will be the length of the materials to be used.

A flexible cover material 17 is first placed in the tray with its side edges overhanging the sides of the tray. Cushioning material 18 is then placed on top of the cover material and pressed down into place to give a preliminary rounding of the corners of the assembly, after which the base member 19 is placed on top of the cushioning member and adhered to it. The leading ends of the cover material are then manually brought up over the sides of the cushioning material and the side edges are pulled into overlapping relation with the base member 19. In doing this, the cushioning is put under slight compression so that the resilient tendency of the cushioning to return to its original condition will exert some pressure against the cover material and hold it taut and smooth. When the cover material ends are in position over the side edges of the bottom, a staple 20 is inserted at each corner to hold the cover in position. Obviously, the cover material behind the staple point will tend to open up to its original flat position. However, the original fold-over the bottom edge has been made and the position of the cover edges established.

The assembled materials in the tray, with the staples at the leading end, will be lying on the support rollers 11 and the entire assembly can be moved along the entrance end 9 toward the operating section of the machine.

As the tray with its assembled kneeling bench components approaches the operating portion of the machine, it first passes between a pair of positioning rollers 21 which fix the position of the tray transversely of the supporting rollers to align it for subsequent operations. These rollers bear against the sides of the channel members 15 of the tray to position the tray itself. Each roller is mounted on an arm 22 which is pivotally connected at 23 to a bracket 24 fixed to the outside of the angle members 7. The pivot 23 for the arm is formed by a bolt, which permits the arm to be adjusted to any angle relative to its bracket and then, by tightening the bolt, maintained at the desired angle. This will not only allow the arms to be adjusted for shifting the tray position laterally, but it will also allow the rollers to be moved toward and away from one another for adjustment for trays of different widths.

As the tray continues past the rollers 21, the base member 19 of the assembly rides under a positioning wheel 25 which is set to determine the height of the horizontal plane in which the bottom member of the assembly will be held through the operating portion of the machine. The wheel is carried in a mount 26 which has a vertical post 27. Post 27 has a sliding fit within a vertical sleeve 28 carried by the front cross bar 6 of the frame. A set

screw 29 in the sleeve 28 will hold the post fixed within the sleeve with the wheel 25 at the desired height. Wheel 25 is located midway between the vertical posts 2 transversely of the frame, so as to ride substantially along the middle of the kneeling bench base member 19.

As the assembled materials on the tray move forwardly beyond the wheel 25, they pass between a pair of angularly positioned rollers 30. These rollers are located on opposite sides of the tray path, and their angle is such that their rotational axes converge upwardly. The rollers contact the assemblies along the upper corners and serve to exert some downward pressure on the edge of the kneeling bench base member, and, at the same time, turn over the upstanding edges of the cover material to a position angularly overlying the edges of the base member to give the cover member an initial partial fold prior to reaching turning elements to be described. Each roller is mounted in a U-shaped bracket 31 having an outwardly projecting mounting bar 32. Bars 32 are slidably supported upon angle members 33, carried by the upper frames 5. The members 33 have horizontal ears 34 overlying the mounting bars 32 and carrying set screws 35 which can be tightened upon the mounting bars 32 to frictionally bind these bars in adjusted positions on the angle members 33. The mounting bars are adjustable transversely of the machine, toward and from the tray path to accommodate kneeling bench assemblies of different widths and to position the rollers 30 to bear upon the upper edges of the assembly with just the proper amount of pressure.

The assembled materials next move under a plurality of hold-down rollers 36, 37 and 38. These rollers are similar in structure and function to the roller 25. The rollers 36 and 37 are axially aligned in spaced relation transversely of the machine, while the roller 38 is located behind the other two, and is in longitudinal alignment with the roller 25 to ride along the mid-section of the kneeling bench base member. These three rollers are carried on a U-shaped pivoted frame 39 having side arms 40 and a bridge member 41. The outer ends of the arms 40 are mounted on corner posts 2 by means of pivots 42. The pivotal mounting of the frame permits it to tilt vertically to raise and lower the bridge member 41. Arms 40, adjacent their juncture with the bridge member 41, carry adjusting screws 43, pivotally connected to the arms at 44. The lower portions of the screws are threaded and project through openings in brackets 45 connected to the upper side frames 5, and nuts 46 and 47 permit adjustment of the screws 43 vertically to hold the frame in desired positions of adjustment. Rollers 36 and 37 are rotatable in mounts 48 and 49 which seat beneath the bridge member 41 of the frame 39. The mounts carry, respectively, brackets 50 and 51 with set screws 52 and 53 positioned to bear against the upper side of the bridge member 41. This permits the rollers to be adjust transversely of the frame to different distances from the longitudinal center of the tray path. Roller 38 is supported in a mount 54 having a vertical post 55. The post is vertically slidable in a sleeve 56 carried by a bracket 57 secured to the rear side of bridge member 41 of the frame 39. A set screw 58 in the sleeve holds the post at various positions of adjustment, so that roller 38 may have the same bearing pressure upon the assembled materials as the rollers 36 and 37.

Directly beneath the hold-down rollers 36 and 37, there are two drive rollers 59 and 60 fixed to a drive shaft 61 mounted in bearings 62 seated on plates 63 projecting from beneath the angle members 7. The tops of the drive rollers 59 and 60 are above the plane of the tops of the rollers 11 forming the tray support path so as to raise the tray from the path and insure frictional driving contact of the tray with the rollers. By proper adjustment of the hold-down rollers 36 and 37, a fixed distance is provided between the hold-down rollers and the drive rollers to assure the required compression of the cushioning ma-

terial and the proper bearing pressure of the tray upon the drive rollers for non-slipping driving.

Roller shaft 61 also carries a sprocket 64 which is driven by a chain 65 from a sprocket 66 on the output shaft 67 of a gear reducer 68. The gear reducer is mounted on the base frame 3, and is driven by a motor 69 also mounted on the base frame. The motor shaft 70 and the reducer input shaft 71 are shown as in line and directly coupled.

Gear reducer output shaft 67 also carries a sprocket 72 which, by means of a chain 73, drives a sprocket 74 on a second drive shaft 75 near the exit end of the machine. The drive shaft 75 carries additional drive rollers 76 and 77, similarly located to the drive rollers on the shaft 61 near the entrance end of the machine. Directly above the drive rollers 76 and 77, are additional hold-down rollers 78 and 79 carried by a pivoted frame 80. The rollers are in mounts 81 and 82 which have brackets 83 and 84 carrying set screws 85 and 86, similar to the mounts for the hold-down rollers 36 and 37, so that the rollers 78 and 79 may be adjustably positioned along the bridge member of the pivoted frame 80. Adjusting screws 87 are pivotally attached at 88 to the side arms of the frame 80, and pass through brackets 89 on the angle members 7, in the same manner as the adjusting screws 43 for the frame 39.

From the foregoing, it will be apparent that the assembled materials on the tray are driven by the rollers 59 and 60 and 76 and 77 adjacent opposite ends of the machine, and the assembled materials are held in compressive contact with these rollers by means of the hold-down rollers 36, 37 and 38 at the entrance end 78 and 79 near the exit end. This assures precise compression of the materials throughout the working area intermediate the driving rollers and parallelism between the tray and the base member of the kneeling bench materials as the assembly moves through cover material edge-folders, edge-tensioners and stapling units to be described.

The first operating station at which the assembled materials arrive in their passage through the machine is the cloth edge-turning station 90. At this station, there are edge-turners 91 located at each side of the tray path to turn, or fold, the upstanding edges of the cover member over the outer, longitudinal edge portions of the base member, and to hold the turned over cover edges in this position as they leave the station. Each edge-turner includes a turning head having a vertical wall 92 which lies close to the edge of the assembled materials and is substantially parallel to the side edge of the assembled materials, and a turning flange 93 overlying the top edge of the assembled materials. The leading edge 94 of the turning flange is raised above the top plane of the assembled materials and is inclined from its juncture with the vertical flange 92 towards its free edge. The trailing edge 95 of the turning flange 93 is substantially parallel to the tray path and will be flush with the turned-over cover material edge as the assembled materials move under it. The turning flange is designed to present a smooth under surface gradually changing from the raised inclined leading edge to the horizontal trailing edge. As the upstanding edge of the cloth reaches the leading edge and proceeds under the turning flange, it will be gradually turned over until it is flat against the exposed surface of the base member of the kneeling bench. The substantially flush arrangement of the trailing edges serves to hold the cover material in its turned over position in contact with the surface of the base member.

The turning heads of the edge-turners have their vertical flanges 92 joined to horizontally extending mounting bars 96. The mounting bars are slidably supported upon the bottom flanges of mounting brackets 97 attached for vertical adjustment upon upstanding frame legs 98 secured at their lower ends to the side walls of the angle members 7 which support the rails of the tray path. The vertical adjustment is accomplished by means of bolts 99, 75

which extend from the brackets through vertical slots 100 in the legs 98. Mounting brackets 97 carry set screws 101 which pass through the upper flanges of the mounting brackets to contact the mounting bars 96 and hold them in position. This construction allows the mounting brackets to be raised and lowered for assemblies of different height and for the edge-turners to be moved laterally of the tray path to accommodate assemblies of different width.

The next operating station in the line is the cover edge-sweeping and tensioning station 102. At this station, there are rotary brushes 103 positioned on each side of the tray path overlying the assembled materials. The brushes are positioned transversely of the tray path, but have a slight forward angle in the direction of travel of the tray and assembled components. This position will enable the brushes, which are rotating in directions to cause their bottoms to move inwardly of the assembled materials, to sweep over the turned edges of the cover to press the cover into firm engagement with the base member surface and to pull the edges of the cover inwardly to draw the cover taut and hold it in this condition as it approaches the stapling units. Each brush is mounted on its own motor 104, and the motors are connected to mounting bars 105 which are secured in brackets 106 mounted for vertical adjustment on the frame legs 98. The adjustment of the brackets on the leg is by means of bolts 107 through slots 108 in the brackets. Mounting brackets 106 carry set screws 109 to hold the mounting bars in positions of lateral adjustment. Here, again, provision is made for raising and lowering the brushes and for moving them inwardly and outwardly relative to the tray path.

While the cover edges are smooth and under tension just after leaving the station 102, the assembled materials arrive at a stapling station 110. Here, stapler units 111 at each side of the tray path are brought into operative contact with the top of the folded over cover edges in rapid succession as the assembly moves along the path, to drive staples through the cover edges and into the rigid base material at predetermined spaced intervals along the cover material. The mountings for the stapler units are such that the units can be moved in and out relative to the tray path, and vertically to increase or decrease their operating heights, and the entire unit can be tilted to raise and lower the stapler units from and to operative, stapling position with respect to the assembled components moving along the path.

The stapling unit is shown including a gun 112, of any conventional type, having a staple magazine 113. The gun has horizontally extending side flanges 114. The mount for the gun consists of a base block 115, and base, intermediate and top hinge leaves 116, 117 and 118. Base block 115 is permanently fixed to the underside of the base hinge leaf 116. Base hinge leaf 116 is hingedly connected at its back end 119, to one end of the intermediate hinge leaf 117, and the opposite end of the intermediate hinge leaf is hinged, as at 120, to the forward end of the top hinge leaf 118. This arrangement is most clearly shown in FIG. 5 of the drawings. At its outer end, the base block has threaded ears 121 which receive threaded adjustment screws 122. Rotation of the screws will raise or lower the top ends of the screws, and the screws can be held in positions of vertical adjustment by means of lock nuts 123. The outer end of the intermediate hinge leaf 117, that is, the end remote from the hinge connection 119 of the intermediate hinge with the base hinge, rests upon the tops of the adjusting screws 122. Thus, the angle between the base and intermediate hinge leaves can be increased or decreased by setting the adjustment screws. At its inner end, the base block 115 carries additional ears 124 to receive a second set of adjustment screws 125. These screws are held in positions of vertical adjustment by means of lock nuts 126. The inner end of the top hinge leaf 118, that is, the free end of the hinge leaf, rests upon the tops of the adjusting

screws 125. By this arrangement, the angle between the base hinge leaf and the intermediate hinge leaf can be increased or decreased to raise or lower the hinge 120 from or toward the base hinge leaf 116 by adjustment of the screws 122, and then the top hinge leaf can be brought into parallelism with the base hinge leaf by adjustment of the screws 125. This permits maintaining the base and top hinge leaves in parallelism while permitting adjustment of the distance between these two hinge leaves.

The side flanges 114 of the stapler gun rests upon the top hinge leaf 118. The gun is held in positions of adjustment longitudinally of the hinge leaf by means of a hold-down bracket 127 which has side angle members 128 with horizontal flanges 129 to seat upon the side flanges 114 of the stapler gun. The side flanges of the hold-down bracket have apertures 130 to receive the stems of tie-down bolts 131 which are pivotally connected at 132 to ears 133 projecting from the base hinge leaf 116. With the bolts 131 through the openings 130 in the hold-down brackets, and the stapler gun in proper adjusted position on the top hinge leaf 118, nuts 134 are threaded onto the ends of the tie-down bolts and tightened to lock the stapler gun to the top leaf of the mount. When these nuts are tightened, they not only secure the stapler gun rigidly in position, but they also serve to lock the entire mount in position to hold the top leaf rigidly upon its adjusting screws 125 and the intermediate leaf tightly against its adjusting screws 122. Thus, the entire unit can be locked, but the stapler gun can be moved in and out and raised and lowered.

The entire unit is pivotally attached to the frame by means of a hinge 135 which has one leaf connected to the bottom hinge leaf 116 of the stapler mount and its other leaf fixedly secured to the outer edge of the upper side frame 5 of the machine frame. This permits the entire stapler unit, after setting and locking, to be tilted about the hinge connection 135 to raise and lower the stapling gun from and to stapling position.

After the assembled components have been stapled, the operation is completed. The completed article then passes out of the machine by moving first between a second pair of inclined side guide rollers 136, which are identical to the inclined rollers 30 at the entrance end. The rollers 136 are supported in U-shaped brackets 137 having mounting bars 138. Angle support members 139, mounted on the upper side frames 5, provide seats for the mounting bars, and set screws 140 in the angle members hold the mounting bars at desired positions of adjustment along the angle members.

The completed unit moves on beneath the rollers 78 and 79 and over the drive rollers 76 and 77. The drive rollers exert a pulling force to assist in drawing the tray and its kneeling bench through the operating section of the machine and onto the delivery, or exit, end. The rollers 78 and 79 press down on the base member of the bench and maintain it in the same horizontal plane originally set by the hold-down rollers 36 and 37.

In continuing its passage out of the machine, the tray contacts two more pairs of side rollers 141 and 142. These rollers are mounted on arms 143 and 144 which are pivotally connected to the frame at 145 and 146. These sets of rollers are identical to the rollers 21 in construction, manner of adjustment, as well as function.

Intermediate the rollers 141 and 142, there is an additional hold-down roller 147. This roller is rotatably supported in a mount 148 having a vertical post 149. The post is slidably received in a sleeve 150 fixed to the angle member 6 joining the rear pair of corner posts 2 on the main frame. A set screw 151 in the sleeve secures the post in vertical positions of adjustment to maintain the roller 147 at the same horizontal level as the other hold-down rollers of the machine.

After the tray and its completed kneeling bench pass the last pair of guide rollers 142, they ride freely along the support path to a position where the kneeling bench

is removed. The tray can be returned to the starting point for the beginning of another cycle of operation.

Returning now to the stapling station, it will be recalled that the stapler units are mounted for pivotal movement about the hinges 135 to raise and lower the stapler gun to drive staples at spaced intervals as the tray with its kneeling bench components moves beneath the stapler. This is accomplished by means of cams 152 which are mounted on the ends of a shaft 153 journaled in bearings 154 secured to the underside of the angle members 7. Shaft 153 is driven by means of a sprocket 155 mounted on the output shaft 67 of the gear reducer 68. Sprocket 155 is on that end of shaft 67 which projects from the opposite side of the reducer housing from the sprockets 66 and 72. Sprocket 155 carries a chain 156 that drives a sprocket 157 mounted on the cam shaft 153. Thus, the cam shaft is driven in timed relation to the drive for the rollers 59, 60, 76 and 77. Base blocks 115 of the stapler mounts carry cam-following rollers 158 which ride upon the surfaces of the cams 152. The cams may have any shape, depending upon the spacing desired between staples. As shown, they have four rises 159 and four low areas 160. As the cams rotate, the rises will lift the staple mounts so that the stapling guns will be raised from the assembled components. When the rollers ride off of the highs, the staplers can drop with the impact necessary to fire them and drive staples.

The stapler guns shown are air operated, and the guns are connected by flexible hoses 161 to a compressed air tank 162 supported on brackets 163 carried by the front and rear corner posts 2 of the frame.

There are times when it is desirable to lift the staplers out of action, for reloading, for example, and manually operable means are provided for this purpose. This means takes the form of lift rods 164 rotatably mounted in brackets 165 depending from the upper side frames 5. The rods extend the full length of the main frame and have actuating handles 166 at each end. Substantially centrally of the rods 164, directly beneath the stapler units, the rods carry lift cams 167 which, when the rods 164 are rotated, will rise into contact with the underside of the base block 115 of the stapler unit and lift the unit, rocking it about its tilting hinge 135. When the rod has been rotated to the degree necessary to cause the lift cams 167 to rise to a vertical position, the stapler units will be raised to inoperative position, with the cam-following rollers 158 entirely out of contact with the operating cams 152. Thus, even though the remainder of the apparatus should be continued in operation, the staplers will be wholly inoperative. When the handles 166 are rotated back to their inoperative positions, the lift cams will be lowered so as to be entirely beneath any operative level of the stapler units. As the cams 167 move out from beneath the base block 115, the staplers are drawn down to operative position with their cam-follower rollers 158 in contact with the cams 152 by means of coil springs 168. These springs are connected to the base blocks 115 of the stapler units and to the base frame 3. Springs 168 also serve to hold the cam-follower rollers 148 in constant contact with the operating cams 152 during normal operation of the machine.

It will be seen from the above that the machine of the present invention will automatically complete kneeling benches, or articles of similar assembly nature, irrespective of the length of the articles. The machine may be stopped whenever required, and restarted without interference with the regular pattern of operation. It will be noted also that the tray with its assembled components has driving contact on opposite sides of the various operating mechanisms, and the assembly has its upper surface held at a predetermined distance above the bottom of the tray and parallel with the tray. This provides a smooth, continuous tray feed and positions the base member of the article being made and the turned over edges of the cover material at a fixed, predetermined height

relative to the edge-folding, edge-sweeping, and stapling units. All of the various mechanisms of the machine are fully adjustable so that articles of different width or height, or both, can be manufactured with but simple adjustment of the various operating and guide members. Due to the fact that the tray with its assembled components is kept in continuous motion throughout the entire operation, the finishing of the kneeling benches can be accomplished at a very high rate of speed. The simplicity of the machine assures substantially constant operation with little down time for repairs or replacement of parts.

While in the above one practical embodiment of the invention has been disclosed, it will be understood that the particular details of construction shown and described are merely by way of illustration, and the invention may take other forms within the scope of the appended claims.

I claim:

1. A machine for making articles having a rigid base member, a cushion on the base member, and a flexible cover member drawn over the cushion with its side edges folded under the side edges of the base member and stapled to the underside of the base member comprising, a frame, means carried by the frame forming a path through the machine, a tray on the path to receive the components of the article to be made in inverted superimposed assembled position, means to move the tray with its assembled components continuously through the machine, means along the path carried by the frame to fold the side edges of a cover carried by the tray over the side edges of a super-imposed base member as the tray moves along the path, means on the frame beyond the edge-turning means in the direction of tray travel to drive staples through the turned-over cover edges into the underlying base member to staple the cover to the base member, and means to raise and lower the staple-driving means to and from the assembled components on the tray in timed relation to the operation of the means to drive the tray along the path to cause staples to be driven at predetermined spaced intervals along the folded cover edges.

2. A machine as claimed in claim 1 wherein there are means to adjust the edge-folding means positioned vertically and transversely of the path, and means to adjust the stapling means positioned vertically and transversely of the path.

3. A machine as claimed in claim 2 wherein there are means intermediate the edge-folding and stapling means to sweep the folded-over cover edges inwardly of the path.

4. A machine as claimed in claim 3 wherein there are means to adjust the side-sweeping means vertically and transversely of the path.

5. A machine as claimed in claim 4 wherein there are manually operable means to raise the stapling means out of operative position.

6. A machine as claimed in claim 5 wherein there are means along the path to position the tray transversely of the path and to guide it along the path.

7. A machine for making articles having a rigid base member, a cushion on the base member, and a flexible cover member drawn over the cushion with its side edges folded under the side edges of the base member and stapled to the underside of the base member comprising, a frame, horizontal conveyor means extending longitudinally of the frame, a tray supported on the conveyor path to receive the components of the articles to be made in inverted superimposed assembled order, means on the frame to drive the tray and the assembled components continuously along at least a part of the conveyor path, means on the frame on each side of the conveyor path in the area along which the tray is continuously driven to fold the side edges of the cover member over the side edges of the superimposed base member as the tray moves along the conveyor path, stapling means on the frame on each side of the conveyor path beyond the edge-folding means in the direction of tray travel and in the area along

which the tray is continuously driven, means to raise and lower the stapling means from and to the folded-over edges of the cover member on the tray, and means on the frame on each side of the conveyor path to hold the tray against transverse movement during tray travel along the area in which the tray is driven.

8. A machine as claimed in claim 7 wherein there is a cover edge-sweeper on the frame on each side of the conveyor path between the cover edge-folding means and the stapling means, and means to drive the edge-sweepers to impart a pull on the folded-over cover edges inwardly of the conveyor path.

9. A machine as claimed in claim 8 wherein the drive means includes drive rollers raised above the conveyor path for frictional contact with the tray bottom located in advance of the cover edge-folding means and beyond the stapling means in the direction of tray travel, and means to drive the rollers continuously.

10. A machine as claimed in claim 9 wherein there are hold-down rollers on the frame above the drive rollers mounted for contact with the base member of the article to be made to compress the assembled components on the tray, to hold the tray in driving contact with the rollers and to maintain the base member at a predetermined level above the conveyor path.

11. A machine as claimed in claim 10 wherein each edge-folding means includes a head having a trailing end inner surface to conform to the shape of the folded-over cover edge and a leading end inner surface spaced outwardly and upwardly relative to the trailing end inner surface to engage and turn the cover edge as the assembled components move along the conveyor path on the tray.

12. A machine as claimed in claim 11 wherein each stapling means includes a stapling gun and a mount for the gun, the gun mount being pivotally mounted on the frame.

13. A machine as claimed in claim 12 wherein the means to raise and lower the stapling means includes cams engageable with the gun mounts, and means to rotate the cams.

14. A machine as claimed in claim 13 wherein there are manually operated means mounted on the frame to raise the stapling gun mounts to lift the guns from operative position.

15. A machine as claimed in claim 14 wherein the stapling guns are adjustable on the mounts to shift the gun positions transversely of the conveyor path.

16. A machine as claimed in claim 15 wherein the stapling gun mounts are adjustable vertically to raise and lower the gun operative position.

17. A machine as claimed in claim 16 wherein the edge-folding heads and the edge-sweeping means are adjustable vertically and transversely of the conveyor path.

18. A machine as claimed in claim 17 wherein the hold-down rollers are adjustable vertically and the means to hold the tray against transverse movement are adjustable transversely of the conveyor path.

19. A machine as claimed in claim 18 wherein there are inclined rollers positioned on each side of the conveyor path ahead of the edge-folding means in the direction of the tray travel to engage the upper side edges of the assembled components on the tray and partially turn the upstanding edges of the cover member prior to reaching the edge-folding means.
